MANUALLY OPERATED CIGARETTE MERCHANTISING MACHINE CABINET

Walter L. Koch, Livingston, N.J., assignor to Rowe Manufacturing Company, Inc., New York, N.Y., a corporation of New York

Application January 8, 1959, Serial No. 54,091

Term of patent 14 years

(Cl. D52—3)

The figure is a perspective view of a manually operated cigarette merchandising machine cabinet showing my new design. The side portion of the cabinet, the rear portion of the cabinet, and the top of the cabinet, not visible in the drawing, are plain.

I claim:

The ornamental design for a manually operated cigarette merchandising machine cabinet, substantially as shown and described.
